UNITED STATES PATENT OFFICE.

BIRGER LJUNGSTRÖM AND BERTIL ALFRED LJUNGSTRÖM, OF STOCKHOLM, SWEDEN;
SAID BERTIL ALFRED LJUNGSTRÖM ASSIGNOR TO SAID BIRGER LJUNGSTRÖM.

AIR HEATER AND METHOD OF OPERATING SAME.

Application filed May 2, 1927, Serial No. 188,349, and in Great Britain April 12, 1926. Renewed October 11, 1927.

The present invention relates to air-heaters and to an improved method of operation advantageously used in connection with air-heaters utilizing waste or smoke gases from furnaces as heating medium.

In air-heaters, especially of the counter-current recuperative type, corrosive matters condense out of the smoke gases onto the surface of the heat conducting walls, with the result that the walls are corroded right through in a comparatively short time and smoke gases and air mix through the openings produced by said corrosion, thus rendering the air-heater unfit for further use.

The corrosion appears chiefly in the colder part of the air-heater and is caused by the low temperature of the entering air cooling the walls of the air-heater well below the temperature at which the corrosive matters contained in the smoke gases condense.

The present invention has for its object to remove the above explained difficulties.

To this end, the present invention provides a method of operating air-heaters of the type in which air, before passing into a furnace or the like, is heated by means of the smoke gases from the furnace or the like, which consists in mixing the air to be heated, with hot air or smoke gases taken from a suitable hot air supply or a suitable smoke gas supply located in front of the smoke gas exhaust of the air-heater, counted in the direction of movement of said gases, in order to maintain all parts of the heat-transmitting walls of the air-heater at a temperature above that at which condensation of corrosive matters from the smoke gases takes place. By this means corrosion of the heat transmitting walls of the air-heater is prevented or at any rate kept within practicable limits.

In most cases an increase of about 50° C. in the temperature of the air prior to being heated in the air-heater proper is found sufficient to raise the temperature of the walls of the air-heater above the boiling point of water (100° C.).

The preliminary heating of the air to be mixed with the cold air supply may be effected by an auxiliary air-heater either separate from or integral with the air-heater

proper. Such auxiliary air-heater may either be built of corrosion resisting material or may be provided with easily replaceable walls or passed by the hot smoke gases prior to entering the air-heater proper in which case the resulting high temperature of the auxiliary air-heater prevents condensation of and corrosion by corrosive matters.

A second method of heating embodies the by-passing of hot gases to be mixed with the air before heating in the air-heater proper, such by-passing starting either from the hot air exhaust or the smoke gas supply of the air-heater proper. A fan arrangement coupled to the by-pass for the heating gases may be provided, if necessary.

If, however, the by-pass is led from the hot air side to the suction side of the fan producing the air pressure necessary for the air-heater proper an extra fan in the by-pass will in most cases be unnecessary.

In many cases only fifteen to twenty per cent of the total volume of the hot gases need be carried by the by-pass.

The hot gases ought to be well mixed with the air to be heated, for which purpose special arrangements are embodied in the invention.

In order more clearly to understand the invention, reference is made to the accompanying drawings which illustrate by way of example some embodiments of arrangements according to the invention.

In said drawings:—

Fig. 1 is a side view of an air-heater provided with a by-pass from the smoke gas supply to the air inlet, the by-pass being fitted with a fan.

Fig. 2 is a side elevation of an air-heater showing a by-pass between the hot air outlet and the suction side of a fan for the cold air.

Fig. 3 is a section parallel to the axis of the fan of Fig. 2 and of the end of the by-pass at the suction side of the fan.

Fig. 4 is a cross section through the end of the by-pass and the fan rotor.

Fig. 5 is a cross section parallel to the axis of the fan fitted with another arrangement for the inlet of the hot gases from the by-pass.

Fig. 6 shows a cross section of the fan rotor and inlet tubes for the same arrangement.

Fig. 7 is a section through the axis of a fan showing the heating gases introduced into the diffuser of the fan.

In Fig. 8 is shown a longitudinal section of the air inlet pipe to the air-heater together with an arrangement for introducing the heating air into the pipe.

Fig. 9 is a cross section of the same arrangement.

Fig. 1 shows a side view of an air-heater 10 having air passages 11 and exhaust passages 13 leading to and from said heater with the air inlet 11' of the heater receiving air through the passage 11 and also heating gases through the by-pass 12 connected to the inlet 13' for hot smoke gases, these gases being transferred through the by-pass 12 by the aid of the intermediate fan 14.

Fig. 2 shows the air passage 11' of the air-heater 10 fitted with a fan 15 supplying air to the air-heater and receiving at the centre of its suction side the hot air from the by-pass 12 starting from the hot air outlet 16 of the air-heater, the smoke gas inlet being designated by 13' and the outlet therefor by 25.

Fig. 3 shows the same fan 15 in longitudinal section with the end 18 of the by-pass pipe 12 situated inside the fan rotor 17.

As shown in Fig. 4, the end 18 is provided around its periphery with longitudinal openings adapted to bring the issuing hot air in rotation inside the fan rotor 17, resulting in the thorough mixing of the hot and cold air.

In Fig. 5 an arrangement for the same purpose is shown in longitudinal section. In this case the by-pass 12 is connected to an annular chamber 19 located around the suction inlet of the fan. From this chamber, tubes 20 are axially and symmetrically disposed at the inside of the circumference of the fan rotor 17.

Fig. 6 shows the tubes 20 and rotor 17 in cross section. The tubes 20 are slotted along their outer edges so as to cause the hot air to issue in a more or less tangential direction.

Fig. 7 illustrates the fan 15 fitted with a bent part of the by-pass 12 arranged around the diffuser of the fan 15, tubular tangential connections 23 being provided between the pipe and the interior of the diffuser.

Fig. 8 is a longitudinal section through the air passage 11 of the preheater. This passage 11 is fitted with an outside annular chamber 21 receiving hot gases from the by-pass 12 and conducting the same into the passage 11 with the aid of intermediate tangential nozzles 22 shown also in Fig. 9.

The hot gases are also in this case put into rotation for the purpose of effecting a thorough mixing with the inlet air.

In the foregoing we have described only a few means for carrying our invention into practical effect. It should, however, be well understood that the invention also includes other alternatives to the same effect as for example taking the heating gases directly from the boiler supply or from another auxiliary air-heater or similar measures.

What we claim is:—

1. In a method for preventing condensation of corrosive matters in exhaust gases traversing an air preheater, the step of preheating the air prior to entrance in the preheater by a fluid having a temperature higher than that of the exhaust gases leaving the preheater.

2. In a method for preventing condensation of corrosive matters in exhaust gases traversing an air preheater, the step of mixing the air prior to entrance in the preheater with a heated fluid of a temperature higher than the temperature of the exhaust gases leaving the preheater.

3. In an air preheater, a passage for air to be heated, a passage for hot gases to be cooled, means permitting heat exchange between the air and hot gases, and means for preventing condensation of cooled gases in said preheater comprising means for preheating the air by a heated fluid having a temperature higher than that of the exhaust gases leaving the preheater.

4. In an air preheater, a passage for air to be heated, a passage for hot gases to be cooled, means permitting heat exchange between the air and hot gases, and means to preheat the air before entrance into the preheater with gas having a temperature higher than that of the exhaust gas leaving the preheater.

5. In a method for preventing condensation of corrosive matters in exhaust gases traversing an air preheater, the step of mixing the air prior to entrance in the preheater with heated air having a higher temperature than the temperature of the exhaust gases leaving the preheater.

6. In an air preheater, a passage for air to be heated, a passage for hot gases to be cooled, means permitting heat exchange between the air and hot gases, means to preheat the air before entrance into the preheater comprising a by-pass for conducting a portion of the heated air from the air outlet of the preheater to the air inlet of the preheater.

7. In an air preheater, a passage for air to be heated, a passage for hot gases to be cooled, means permitting heat exchange between the air and hot gases, and means to preheat the air before entrance into the pre-

heater comprising a by-pass for conducting a portion of the heated air from the air outlet of the preheater to the air inlet of the preheater and devices for intimately mixing the two fluids.

8. In an air preheater, a passage for air to be heated, a passage for hot gases to be cooled, means permitting heat exchange between the air and hot gases, and means to preheat the air before entrance into the preheater comprising a by-pass for conducting a portion of the heated air to the inlet of the air passage and devices for intimately mixing the two fluids including nozzles for introducing said heated air into said other air.
9. In an air preheater, a passage for air to be heated, a passage for hot gases to be cooled, means permitting heat exchange between the air and hot gases, and means to preheat the air before entrance into the pre-

heater comprising a by-pass for conducting a portion of the heated air to the inlet of the air passage and devices for intimately mixing the two fluids including nozzles for introducing said heated air into said other air, said nozzles being arranged to impart rotary motion to said heated air after delivery from the nozzles.

10. In an air preheater, a passage for air to be heated, a passage for hot gases to be cooled, means permitting heat exchange between the air and hot gases, and means to preheat the air before entrance into the preheater comprising a by-pass for conducting a portion of the heated air to the inlet of the air passage and a fan in said by-pass.

In testimony whereof we affix our signatures.

BIRGER LJUNGSTRÖM.

BERTIL ALFRED LJUNGSTRÖM.
